UNITED STATES PATENT OFFICE.

WINFIELD B. PHILLIPS, OF FENTON, MICHIGAN.

WINDOW-SCREEN.

1,071,339.

Specification of Letters Patent. Patented Aug. 26, 1913.

Application filed June 28, 1910. Serial No. 569,380.

To all whom it may concern:

Be it known that I, WINFIELD B. PHILLIPS, citizen of the United States, residing at Fenton, in the county of Genesee and State of Michigan, have invented certain new and useful Improvements in Window-Screens, of which the following is a specification.

The present invention relates to screens and more particularly, the invention is designed to provide in a screen, a novel construction and arrangement of parts looking to a reduction in the cost of manufacture, efficiency in operation, and combining strength and durability with lightness.

It is a matter of common knowledge that screen sections formed of wood with parts slidably interlocked, will, in the course of time, warp or split or swell and become forced into wedging contact at their connecting joints, thus rendering it difficult to adjust the sections.

In an endeavor to overcome the above difficulties, it has been proposed to construct an all-metallic screen or a screen in which the framework is wholly of metal, but all of these constructions, with which I am familiar, are more or less faulty because of their weakness, and the tendency to wobble, bend or buckle. It has also been proposed to reinforce the screens which are formed wholly of metal at the corners thereof, since if the corner joints are not reinforced with an extra corner piece, they are so weak that the frames readily collapse, but such constructions have proven objectionable, because of the increased cost incident to the metallic joints at the corners and the likelihood of said corner pieces becoming detached.

It is contemplated by the present invention to overcome existing defects and may be said to comprise screen frame sections, the sides of which are wood, and the interlocking tops and bottoms of which are of metal formation throughout, with the result that any binding at the slideable interlocking parts is absolutely provided against, and at the same time the sides are rigid and effectively resist the shock of slamming the sash down upon the screen. The improved method of corner construction provides

rigid and stiff frames, insuring the greatest possible strength and durability at the smallest manufacturing cost. 55

Other improvements and novel details in the construction and arrangement of parts will be more particularly referred to hereinafter, and the description to follow should be read in connection with the accompanying drawings, forming a part hereof, and wherein is disclosed, for the purpose of illustration, a satisfactory embodiment of the invention. 60

In the drawings, Figure 1 is a front view of a screen comprising two sections slidably interlocked, Fig. 2 is an end view of one section, Fig. 3 is a perspective view of one corner cut away, Fig. 4 is a detail view of the interlocking connection between the screen sections, Figs. 5, 6 and 7 are detail sectional views. 65

Referring more particularly to the drawings, like reference numerals refer to corresponding parts throughout the several views, 75 and the screen is shown as comprising two sections slidably interlocked one with the other, whereby the screen is adapted to fit windows of various widths. One of the screen sections is preferably made up of an end frame in two parts, the lower one 1, and the upper one 2, being of wood construction and preferably solid throughout, the sections 1 and 2 being secured together in any desired manner as by nails or the like 3, and adapted to support therebetween one edge 80 of the screen member 4. The top and bottom frame members of this screen section are of metallic formation throughout, and are substantially the same in construction, so 85 that a description of one will suffice for the other. In forming the top and bottom frames, an elongated strip of sheet metal or the like is provided, the same being bent longitudinally upon itself thereby presenting a double thickness for added rigidity and strength. The free edges 5 and 5^a are 90 adapted to overlie the adjacent edges of the screen and be secured thereto if desired, but it is found in practice that this securing means may be done away with, since the edges 5 and 5^a are adapted to rest in a recessed portion 1^a at the end of the bottom end section 1, and in this way will friction- 100

ally hold or clamp the screen. The edges 5 and 5^a are secured in position through the medium of nails or the like passing through the top end section 2. The metallic strips 5 are then bent longitudinally so as to present an angled extension 7 adapted to fit over the end of the end frame section 1, and said metallic strip is further bent longitudinally, to present an angled section 8, which overlies 10 the under surface of said end section 1. Securing nails or the like pass through the metallic strip and the end of the section 1, as at 8', and similar securing devices pass through the metallic strip and under surface 15 of the end section 1, whereby the metallic strip is secured at a plurality of points and firmly supported thereby. It is observed that since the metallic strips constituting the top and bottom frames of the 20 section extend over the end of the end section 1, the groove or guideway formed between the bent edges of said strip is provided with a filling at its end tending to prevent any collapsing and maintaining a 25 practically uniform guideway or groove for the interlocking tongue formed by the top and bottom frames of the coöperating section.

The coöperating section of the screen comprises an end frame made up of the lower part 9 and upper part 10 secured to one another as by nails 11, said parts being constructed of wood, as are the parts 1 and 2 of the coöperating section, and adapted to support therebetween the edge of the screen member 12. The top and bottom frame members of this screen section comprise metallic strips, conveniently sheet metal, bent longitudinally upon themselves with the 35 free edges 13 and 14 thereof overlying the adjacent edges of the screen member 12. This metallic strip is bent at an angle intermediate its ends, the angle portion 15 being of a width to freely play in the groove 40 formed by the coöperating metallic frame of the other screen section, whereby the screen sections are free to slide relative to one another. The overlying free edges 13 and 14 of the metallic strip are arranged to rest 45 within a recessed portion 9* in the end of frame member 9 and to be secured in position by nails or the like passing through the other end frame section 10. Again, the angled flange 15 of the metallic strip fits over 50 the end of the end frame part 9 and is secured thereto as by nails or the like 15*. The inner edges of the screen member are supported between overlying edges 16* of metallic brace bars 16, which latter are conveniently of sheet metal construction and have flat ends 16^b fitting between the free edges of the folded metallic top and bottom frame sections, and secured by means of 55 nails or the like at 16*. These brace bars 16

are laterally offset at 17, said offset portion 65 adapted to contact with the screen of the co-operating section, thereby providing a close fit, and the offset portions of the respective brace bars constituting means for limiting the outward sliding movement of the screen 70 sections, and preventing separation thereof.

By the construction just described, it will be appreciated that a very strong and durable screen is provided, one which is efficient in operation, since the interlocking sliding 75 connections are free from any binding action or swelling and warping incident to weather influences, and at the same time the screen is strong and durable since the end parts or sections are of solid wood construction, 80 thereby reinforcing the sheet metal construction of the interlocking sections and affording means capable of withstanding the jars and slamming of the window upon the screen in the usage of the same. Again, it should 85 be borne in mind that were the end sections of the screen formed of metal, the weight will not only be increased, but the expensive constructions at the ends looking to rigidity will vastly increase the cost of production. 90

I claim:

1. In a screen, oppositely disposed side frame members of wood, and top and bottom frame members of metal, the top and bottom frames having projecting end portions covering the ends of the wooden frames and secured to the latter, and a suitably connected screen. 95

2. In an extensible screen, a plurality of sections, each comprising an end frame 100 member of wood and top and bottom frame members of metal, the metallic frame members overlying at their outer ends the ends of the wood frames and the top and bottom member of each frame being slidably interlocked. 105

3. In an extensible screen a plurality of sections, each comprising an end frame member of wood and top and bottom frame members of metal, the metal frame members comprising a strip fitted in recesses in the ends of the side members and having angled extensions resting on the ends of said side members and slidably interlocked with one another. 110

3. In an extensible screen, a plurality of screen sections, each comprising a side member formed of wood, sheet metal top and bottom frames, the sheet metal top and bottom frames having a direct slidable interlocking connection one with the other, and the outer ends of the metal frames overlying the ends of the wooden frames and secured to the latter. 115

5. In an extensible screen, the combination of screen sections, each comprising a side member formed of wood, sheet metal top and bottom frames, the sheet metal top

and bottom frame of one section being bent upon itself to constitute a guideway, and the sheet metal top and bottom frame of the other section being bent upon itself to constitute a tongue for engaging said guideways, and each metal frame having a vertically extending part fitting in a recess in the wooden frames and a laterally offset part

overlying the ends of said frames and secured to the latter.

In testimony whereof I have affixed my signature in presence of two witnesses.

WINFIELD B. PHILLIPS.
